SEWING MACHINE

Patented April 11, 1865.

DES. 2042

Caleb Cadwell of Hawkeye, Illinois.

Letters Patent No. 2642 - Dated April 11, 1865.

Design for a Sewing Machine.

The schedule referred to in these Letters Patent and making part of the same.

To all whom it may concern:

Be it known that I, Caleb Cadwell, Hawkeye, in the County of Lake and State of Illinois have invented a new and ornamental design for sewing machines, and I do hereby declare the following to be a full and exact description of the same, referring to the accompanying drawing which makes part of this specification and which represents a perspective view of my sewing machine.

My design consists essentially of a sewing machine with a circular casing A and an upper horizontal arm or extension B, together with a lower arm C for the attachment of the feet or supports.

The circular casing may contain the whole of the driving mechanism which may be located within the extension B, the latter serving as the working table.

The machine thus formed is elegant and graceful in appearance and susceptible of ornamentation and embellishment in the highest degree.

Having thus described my invention what I claim as new therein and desire to secure by Letters Patent is

A design for sewing machines, consisting of the circular casing A, horizontally projecting arm B, and lower extension or arm C, as herein described and represented.
